UNITED STATES PATENT OFFICE.

WILLIAM WEIR, OF CATHCART, SCOTLAND

LIFT-VALVE AND ITS GUARD FOR GAS AND LIQUID PUMPS.

No. 852,589.

Specification of Letters Patent.

Patented May 7, 1907.

Application filed June 2, 1906. Serial No. 319,876.

To all whom it may concern:

Be it known that I, WILLIAM WEIR, a subject of the King of the United Kingdom of Great Britain and Ireland, and residing at 5 Cathcart, Renfrewshire, Scotland, have invented certain new and useful Improvements in Lift-Valves and Their Guards for Gas and Liquid Pumps, of which the following is a specification.

10 This invention relates to improvements in and relating to lift valves and to guards therefor for use in pumps dealing with gases and liquids, and is designed to render such valves more efficient, lighter, and less costly 15 as also more reliable against breakage and leakage.

20 In the accompanying drawing which illustrates the invention and in which like parts are similarly designated Figure 1 is a vertical section of one form of the improved lift valve and guard; Fig. 2 is a like view but showing a modification; Fig. 3 is a plan of the valve; Figs. 4 and 5 are vertical section and plan respectively of a further modification.

25 According to the invention the valve A is, in the case of all the constructions shown, formed by pressing, stamping or spinning from metallic sheets or from a forged disk of ductile material. The sectional form of the 30 valve is as shown that of an annular ring with a groove or arched passage B formed between the two seating faces D. The outer wall C of the passage B is utilized in conjunction with the guard F for guiding the valve 35 during its lift.

40 Referring to Fig. 1 the improved guard F is as above mentioned formed by pressing, stamping or spinning from a metallic sheet or from a forged disk of ductile material, an annular disk with a central flat portion or depression G between which and the circumference of the disk an annular passage H is formed by the downward flanging of the outer 45 circumference. The circumferential flange or wall J forms the guide for the valve A and the crown K of the annular passage H forms the stopper for limiting the lift of the valve.

45 According to the construction of the guard F shown in Fig. 2 there is formed between the central flat portion G and the outer circumferential guiding wall or flange J an additional annular arched passage H' into which can be placed a spring L bearing on the 55 crown of the passage or arch.

In both constructions the guard F is se-

cured to the seat D¹ by means of a screwed stud or studs M fixed in the seat and projecting through the flattened central part G of the guard F and held by means of a nut M¹. 60 Openings N are made in the guard F between the flange J and the central portion G to allow free passage for air or liquid.

According to the modification shown in Figs. 4 and 5 the guard F is formed as an annular ring having a depression G between two arched passages H substantially of the same contour as that shown in Fig. 1. This arrangement provides a guard for two annular valves A. In this case the guard F is 70 also held in position by the studs M in the seat D¹ passing through the depression G and having securing nuts M¹ on the studs. The exact shape of the groove or arched passage B in the valves A may vary but preferably 75 the crown of the passage B is semi-circular and the guiding wall C is curved slightly, the curve preferably being of a diameter approximately equal to the diameter of the guiding wall itself. This prevents any tendency for 80 the valve to become jammed in the guard F.

Having now described my invention, what I claim and desire to secure by Letters Patent of the United States is:

1. The combination with two concentric 85 annular valves, said valves each presenting in vertical section a form comprising two flat seating faces joined together by a groove or arched passage, of a single valve guard formed to provide a central flattened depression for permitting its attachment to the valve seat, and with an inner and outer flange or guiding wall for guiding the valves during their lift with crowned passages between the central depression and the guiding 90 flanges for limiting the lift of the valves.

2. The combination with a valve seat having two concentric series of openings, of two concentric annular valves, each adapted to close one of said series of openings, and an 100 annular valve guard having a portion adapted for attachment to said valve seat and a depending annular flange on either side of said portion, said annular flanges being constructed and arranged to guide said valves 105 during the lift of the latter.

3. The combination with a valve seat having two concentric series of openings, of two concentric annular valves each presenting in vertical section a form comprising two flat seating faces joined together by a raised portion and each adapted to close one of said se-

ries of openings, and an annular valve guard having a portion adapted for attachment to said valve seat and a depending annular portion on either side of said first-named portion, 5 said depending portions being constructed and arranged to guide said valves during the lift of the latter, said valve guard also having means above said depending portions adapted to engage said raised portions of said 10 valves to limit the lift of the valves.

4. The combination with a valve having a portion raised above the seating portion thereof, of a valve guard having a depending portion arranged to co-operate with the 15 raised portion of said valve to guide the lat-

ter during its lift, and means, carried by said depending portion above the lower edge thereof, adapted to engage said raised portion of said valve to limit the lift of the latter prior to the engagement of the seating portion of the valve with the lower edge of the depending portion of said valve guard. 20

In testimony whereof I have signed my name to this specification in the presence of two subscribing witnesses.

WILLIAM WEIR.
